J. KENNEDY

Des. 161,939

JET PROPELLED ATTACHMENT FOR SPINNING BALLOONS

Filed Sept. 13, 1950

UNITED STATES PATENT OFFICE

161,939

JET-PROPELLED ATTACHMENT FOR
SPINNING BALLOONS

John Kennedy, Detroit, Mich.

Application September 13, 1950, Serial No. 12,164

Term of patent 14 years

(Cl. D34—15)

To all whom it may concern:

Be it known, that I, John Kennedy, a citizen of the United States, residing at Detroit, in the county of Wayne and State of Michigan, have invented a new, original, and ornamental Design for a Jet-Propelled Attachment for Spinning Balloons, of which the following is a specification, reference being had to the accompanying drawing, and forming a part thereof.

Figure 1 is a side elevational view of the jet-propelled attachment for spinning balloons, showing my new design;

Figure 2 is a top plan view of the jet-propelled attachment for spinning balloons; and

Figure 3 is an end elevational view of my jet-propelled attachment for spinning balloons.

The broken lines appearing in Figs. 1-3 of the drawing are intended to represent an expanded balloon from which air is exhausted through the

jets for spinning the balloon. The broken line showing of the balloon is for illustrative purposes only.

I claim:

The ornamental design for a jet-propelled attachment for spinning balloons, as shown and described.

JOHN KENNEDY.
